Attorney.

UNITED STATES PATENT OFFICE.

ALBERTO FARANDA, OF MILAN, ITALY.

VACUUM-DISCHARGER FOR LOWER TENSIONS.

1,354,812.

Specification of Letters Patent.

Patented Oct. 5, 1920.

Application filed January 4, 1919. Serial No. 269,645.

To all whom it may concern:

Be it known that I, ALBERTO FARANDA, engineer, subject of the King of Italy, residing at Milan, Via Ponte Seveso 35, Italy, 5 have invented certain new and useful Improvements in Vacuum-Dischargers for Lower Tensions, of which the following is a specification.

The present invention relates to a safety 10 discharge device for low potentials working with a proper measurement of pressure and without being subject to troubles arising from its working or from mechanical causes.

This object is attained by the use of metal 15 electrodes, the mass and the surface of which are reduced to a minimum, and the disposition of which, as well as the mechanical connection effected by the aid of an interposed insulating substance, is such as to 20 render impossible any change of position or of the relative distance between the electrodes.

The accompanying drawing represents, 25 by way of example, two different types of construction of the device; the type represented in Figure 1 must be essentially regarded as an explanatory diagram, while the type shown in Fig. 2 represents a construction designed to afford a perfect work- 30 ing.

The safety discharge of my invention consists, as shown in the drawing, of two annular metal electrodes A A¹ (preferably of aluminum or silver) provided with stems 35 B B¹ and electrically connected to platinum filaments C C¹ sealed in a glass bulb D containing a highly rarefied gas. The said

filaments are then attached to small external metal caps E E¹ which are electrically connected to the line to be protected. A small 40 cylinder F of insulating and incombustible material, such for example as mica, is inserted in the two annular electrodes and serves to hold them in position.

The sparking distance can be exactly de- 45 termined either by placing the electrode rings in positions inclined to each other (see Fig. 1), or by providing the opposite faces with pins or points arranged upon alternate sectors (as shown in Fig. 2). 50

I claim as my invention:

A safety discharge device for low potentials, consisting in its entirety of the combination of two small annular metal electrodes placed opposite each other; a single 55 small cylinder of insulating and incombustible material inserted through both annular electrodes and on which they are immediately held in position and at a given distance apart; a glass bulb containing a highly 60 rarefied gas and in which the electrodes are arranged, the said bulb being provided at each end with a small metal cap forming contact with the adjacent electric conductor to be protected; and platinum wires at op- 65 posite ends of the bulb connecting said caps to the internal electrodes and sealed in the glass of the bulb; substantially as described.

In testimony whereof I affix my signature.

ALBERTO FARANDA.
